(57) **CLAIM**

The ornamental design for a wireless LAN site survey and rapid deployment kit, as shown and described herein.

DESCRIPTION

FIG. 1 is a perspective view of the wireless LAN site survey and rapid deployment kit of the claimed design;

FIG. 2 is an extended view thereof, showing the mounting pole, collar, clamps, and interior assembly apart from the case;

FIG. 3 is a front view thereof;

FIG. 4 is a right side view thereof;

FIG. 5 is a rear view thereof;

FIG. 6 is a left side view thereof;

FIG. 7 is a top plan view thereof; and,

FIG. 8 is a bottom plan view thereof.

The features shown in broken lines do not form part of the claimed design.

The article is shown with a symbolic break in its length. The appearance of any portion of the article between the break lines forms no part of the claimed design.
